RAZOR BLADE SHARPENER

Thomas Lee Hughes, Fullerton, Calif.

Application November 7, 1933, Serial No. 697,061

7 Claims. (Cl. 51—153)

The objects of this invention are to provide novel means for mounting a blade holder, in a sharpening machine, to provide novel means for operating the blade holder both as to reciprocation and as to reversal about a transverse axis, and to improve the construction of the framework of the machine.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in top plan, a device constructed in accordance with the invention, parts being broken away;

Fig. 2 is a side elevation;

Fig. 3 is a section on the line 3—3 of Fig. 1;

Fig. 4 is a section on the line 4—4 of Fig. 1;

Fig. 5 is a transverse section on the line 5—5 of Fig. 1;

Fig. 6 is a fragmental top plan, with parts being broken away.

In carrying out the invention, there is provided a base 1, which is a box-like structure of small height. The base 1 comprises a bottom 2, an end wall 3, an end wall 4, a side wall 5, and a side wall 6 the side wall 5 being somewhat higher than the side wall 6. Secured to the bottom 2, adjacent the end wall 3 is an outwardly projecting tab 7 having a hole 8 whereby the article may be hung up. Guides 9 are secured to the bottom 2, adjacent to the end wall 4. In the guides 9, a U-shaped handle 10 is slidably mounted. When the device is in use, the handle is drawn outwardly as in Fig. 1, but when the device is not in use, the handle may be shoved inwardly, under the bottom 2, as shown in Fig. 4. There are elongated openings 11 in the bottom 2, which facilitate the removal of the sharpening element hereinafter described. The side wall 5 has a longitudinal guide slot 12 parallel to the bottom 2. The side wall 5 has an outwardly projecting guiding lip 14 at the upper edge of the slot 12. The wall 6 is provided with an inwardly projecting flange 15. The flange 15 is parallel to the bottom 2 and extends between the end walls 3 and 4.

Anchor blocks 16 are disposed under the flange 15, in the two corners formed by the parts 6—4—3. Tubular posts 17 are placed on the inwardly projecting flange 15, near to its ends. The numeral 18 marks a guide rail which is parallel to the bottom 2. The guide rail 18 has flattened ends 19, resting on the upper end of the tubular posts 17. Securing elements 20, such as screws, pass downwardly through the flattened ends 19 of the guide rail 18, through the tubular posts 17, through the flange 15, and into the anchor blocks 16. Thus the posts 17 and the guide rail 18 are connected rigidly to the base 1, in the position shown in Fig. 3. Figure 5 shows that the anchor blocks 16 have another function, in that they serve as abutments for one side of the herein-after mentioned sharpening element.

The sharpening element may comprise the block 21 of Fig. 3, into which a hone 22 is recessed and secured. The sharpening element 75 may be the block 23 of Fig. 4, to the top of which a yieldable cushion 24, made of felt or other material, is secured. The strop 25 is secured to the upper surface of the cushion 24. The operator uses the sharpening element of Fig. 3 or the 80 sharpening element of Fig. 4, depending upon the nature of the work which is to be done to the blade which is to be sharpened. The sharpening element, whatever be its form, is mounted removably in the base 1. The sharpening element 85 abuts at one side against the anchor blocks 16 (Fig. 5) and abuts at its opposite side against the member 5 of the base 1. The ends of the sharpening element (Fig. 4) are engaged by the end walls 3 and 4 of the base 1. 90

The numeral 26 marks a rider, in the form of a vertical plate (Fig. 2). At its ends, the rider 26 has inwardly projecting lugs 27. The guide rail 18 passes through the lugs 27, and, thus, the rider 26 is mounted on the guide rail 95 for reciprocation longitudinally of the guide rail. Intermediate its ends, the rider 26 has a fixed, inwardly projecting, tubular bearing 28. A shaft 29 is mounted for rocking movement in the bearing 28. One end of the shaft 29 slides in the 100 slot 12 of the side wall 5, in contact with the lip 14 of said side wall (Fig. 5). Intermediate its ends, the shaft 29 is supplied with a polygonal portion 30 forming a shoulder 31. A pin 32 or the like, in the polygonal portion 30, forms a 105 second shoulder.

The blade retaining means is a composite structure. It comprises an outer trough-shaped blade holder 33. On the back of the blade holder 33 there is a rectangularly disposed arm 34. The 110

arm 34 is disposed nearer to one end of the blade holder 33 than to the other end thereof. The arm 34 has an oblong opening 35 receiving the squared portion 30 of the shaft 29. The width 5 of the opening 35 is equal to the width of the squared portion 30 of the shaft 29, but the length of the opening is greater (Fig. 4) than the width of the squared portion 30 of the shaft 29. Consequently, when the shaft 29 is rocked on 10 its axis, the blade holder 33 is swung toward and away from the sharpening element, for instance the hone 22 of Fig. 3, but because the opening 35 is longer than the width of the squared portion 30 of the shaft 29, the blade holder can have 15 a lateral swinging movement in the direction of the arrow A in Fig. 1. The shifting of the position of the blade holder 33 with respect to the surface of the hone 22, when the blade is in contact with the hone, is further promoted by reason 20 of the fact that the arm 34 is not located midway between the ends of the blade holder 33, but is slightly near to one end of the blade holder than the other.

Within the resilient outer blade holder 33 is 25 removably held an inner trough-shaped blade grip 36. The blade grip 36 has a projection 37 at one end (Fig. 1). There is an opening 38 in the projection 37. The opening 38 in the projection 37 matches with notches 51 in the ends 30 of the outer blade holder 33. The opening 38 facilitates the removal of the inner trough-shaped blade grip 36 from the outer blade holder 33. The blade 39 which is to be sharpened, is gripped in the inner blade grip 36.

35 On the outside of the plate-like rider 26 (Fig. 2) a pinion 40 is secured to the shaft 29. The pinion 40 meshes with a partial gear 41. The partial gear 41 has extensions 42 at diametrically opposite points. The extensions 42 of the partial 40 gear 41 carry rigid, outwardly projecting finger pieces 43. Sleeves 44 are journaled for rotation on the finger pieces 43 and are held thereon. The rotatable sleeves 44 facilitate the rocking or rotation of the partial gear, at the hand of an operator, by means of the finger pieces 43. The partial gear 41 is supported at its center on the rider 26, for rotation or rocking movement, as shown 45 at 45.

The rider 26 carries a brake mechanism adapted 50 to cooperate with the guide rail 18. The brake mechanism is shown best in Fig. 5. It comprises an outwardly projecting socket 47 on the rider 26. A screw 46 is threaded into the socket 47 and has a finger piece 48 at its outer end. A brake piece 49, which may be made of 55 friction material, is slidably mounted in the inner end of the socket 47 and bears on the guide rail 18. A compression spring 50 is located in the socket 47 and is interposed between the screw 60 46 and the brake piece 49.

In practical operation, the rider 26 is slid back and forth along the guide rail 18, by means of the finger pieces 43 and their sleeves 44, with the edge 65 of the blade 39 in contact with the sharpening element, which may be either the hone 22 of Fig. 3 or the strop 25 of Fig. 4. The blade is reversed between the positions shown in Figs. 3 and 4 by a train of parts comprising the finger pieces 43, the partial gear 41, the pinion 40, the shaft 29, the arm 34 on the blade holder 33.

The brake composed of the screw 46, the spring 70 50 and the piece 48 exert an adjusted pressure on the guide rail 18, the movement of the rider 26 along the guide rail being retarded, and conditions being created which simulate closely those

that exist when an ordinary razor is stropped or honed in the well-known way. The action of the brake on the guide rail 18 serves two purposes. First, it holds the rider 26 at the end of each stroke and prevents the blade 39 from cutting into the strop when the blade is flopped over from the position of Fig. 3 to the position of Fig. 4, for instance, and when the sliding movement of the rider 26 is reversed. Really, the blade 39 is in the same position in Figs. 4 and 3 since the device has been turned end for end in those figures, but they may be used as has been done above, to illustrate the point under discussion.

80 A second use for the brake is that by retarding the movement of the carriage 26, a larger proportion of the force tending to slide the carriage along the rail 18 becomes effective to rotate the gears 41 and 40 and the shaft 29, and 85 the blade 39 is held the more closely on the sharpening element. The pressure of the blade 39 on the stropping element depends on the effectiveness of the brake, and the drag of the blade 39 on the rail 18 may be regulated between minimum and maximum by adjusting the screw 100 46 out or in. The importance of the brake, in the practical working of the device cannot be over-estimated.

90 The foregoing disadvantages are overcome in the device forming the subject matter of this application, since the blade 39 is not constrained to follow the same path as the blade moves back and forth over the stropping element. The blade 39 does not follow a single path because the blade holder 33 can swing laterally, as shown by the arrow A in Fig. 1, and the mounting of the arm 34, nearer to one end of the blade holder 33 than to the other, also changes the path in which the blade moves over the sharpening element. The blade 39 tends to assume other than a rectangular 110 position with respect to the line of reciprocation, and that is proper, as any cutler knows. Since the arm 34 of the blade holder 33 has some latitude of movement on the shaft 29, the blade 39 tends to engage the sharpening element with an 115 even pressure. In general, so satisfactory is the operation of the device that a person having a little practice can work at a speed of two hundred 120 strokes or so per minute.

125 The rider 26 is mounted to reciprocate on the single guide rod 18, but a smooth sliding movement of the rider is effected because the end of the shaft 29 moves in the slot 12 of the side wall 5, in contact with and beneath the lip 14. Practically all of the driving mechanism is mounted 130 on the rider 26, aside from the fact that the end of the shaft 29 moves in the slot 12 of the side wall 5, the construction last above referred to serving to keep the shaft 29 parallel to the working surface of the sharpening element. The power applied to the finger pieces 43 and their sleeves 44 is parallel to the guide rail 18, and the brake mechanism 49—50—46 will not pinch or bind on the rail 18, the friction of the brake on the rail being just what is created by advancing or 140 retracting the screw 46. The posts 17, the screws 20, the anchor blocks 16 and the flange 15 form a simple but effective means for holding the guide rail 18 rigidly in place, in its proper position.

145 The outer blade holder 33 preferably is formed of spring steel, heavy enough to answer the purpose. The inner blade grip 33 preferably is made of lighter spring steel, and the blade 39 may be inserted readily into it, the blade grip 36 then 150

being placed in the stronger blade holder 33. The operator is not confronted with the problem of placing a bare blade into a strong blade holder, an operation which very often brings about a slashing of the operator's hand by the blade. The inner blade grip 36, of course, may be made to accommodate blades of any construction.

What is claimed is:

1. A sharpener of the class described, comprising a base including a sharpening element, a shaft disposed transversely of the base, means for moving the shaft longitudinally of the base and for rocking the shaft, a blade holder, and mechanism for mounting the blade holder on the shaft for swinging movement in a plane approximately parallel to the shaft, in operative relation to the sharpening element, said mechanism embodying a squared portion on the shaft, and an arm on the blade holder, the arm having an oblong opening receiving the squared portion of the shaft, the width of the opening being the same as the width of said squared portion, and the length of the opening being greater than the width of said squared portion.

2. A sharpener of the class described, comprising a base including a sharpening element, a shaft disposed transversely of the base, means for moving the shaft longitudinally of the base and for rocking the shaft, a blade holder, and mechanism for mounting the blade holder on the shaft for swinging movement in a plane approximately parallel to the shaft, in operative relation to the sharpening element, said mechanism embodying a squared portion on the shaft, and an arm on the blade holder, the arm having an oblong opening receiving the squared portion of the shaft, the width of the opening being the same as the width of said squared portion, and the length of the opening being greater than the width of said squared portion.

3. A sharpener of the class described, comprising a base including a sharpening element, the base being provided at one side with a first wall having an inwardly-extended overhanging flange, the base having a second wall at its opposite side, the said second wall having a guide slot, anchor blocks under the flange, posts supported on the flange, a guide rail supported on the posts, securing elements passing through the guide rail, post and flange into the anchor blocks, the sharpening element being engaged between the anchor blocks and the second wall, a rider slidable on the guide rail, a shaft journaled in the rider and slidable in the slot, a blade holder carried by the intermediate portion of the shaft and cooperating with the sharpening element, and means for rocking the shaft and sliding the rider on the guide rail longitudinally of the base.

4. A sharpener of the class described, comprising a base provided at one side with a first wall having an inwardly-extended overhanging

flange, the base having a second wall at its opposite side, the said second wall having a guide slot, anchor blocks under the flange, posts supported on the flange, a guide rail supported on the posts, securing elements passing through the guide rail, post and flange into the anchor blocks, a rider slideable on the guide rail, a shaft journaled in the rider and slideable in the slot, a blade holder carried by the intermediate portion of the shaft, means for rocking the shaft and sliding the rider on the guide rail longitudinally of the base, and a sharpening element located beneath the blade holder, the sharpening element fitting closely but removably between the anchor blocks and the second wall.

5. A sharpener of the class described comprising a base including a sharpening element, a guide rail, mechanism for securing the guide rail to one side of the base, the opposite side of the base being provided with a side wall having an elongated guide slot, a rider slideable on the guide rail, a shaft journaled in the rider and slideable in the slot, a blade holder carried by the shaft between the guide rail and said wall, means for rocking the shaft and sliding the rider on the guide rail longitudinally of the base, with the blade holder in operative relation to the sharpening element, and a brake carried by the rider and engaging the guide rail.

6. A sharpener of the class described comprising a base including a sharpening element, a guide rail, mechanism for securing the guide rail to one side of the base, the opposite side of the base being provided with a side wall having an elongated guide slot, a rider slideable on the guide rail, a shaft journaled in the rider and slideable in the slot, a blade holder carried by the shaft between the guide rail and said wall, means for rocking the shaft and sliding the rider on the guide rail longitudinally of the base, with the blade holder in operative relation to the sharpening element, a brake on the rider and engaging the guide rail, and means for adjusting the pressure wherewith the brake bears on the guide rail. 105 110 115 120

7. A sharpener of the class described comprising a base including a sharpening element, a guide rail, mechanism for securing the guide rail to one side of the base, the opposite side of the base being provided with a side wall having an elongated guide slot, a rider slideable on the guide rail, a shaft journaled in the rider and slideable in the slot, a blade holder carried by the shaft between the guide rail and said wall, means for rocking the shaft and sliding the rider on the guide rail longitudinally of the base, with the blade holder in operative relation to the sharpening element, the means for rocking the shaft and sliding the rider embodying a pinion secured to the shaft, a gear meshing with the pinion and journaled on the rider, and outstanding handle members on the gear at substantially diametrically opposite points.
